UNITED STATES PATENT OFFICE.

JOHN E. W. FOGAL, OF QUINCY, ILLINOIS, ASSIGNOR TO ALBERT E. RUSH, HERMAN H. HEIDBREDER, JOHN E. W. FOGAL, AND C. LAWRENCE WELLS, CONSTITUTING THE FIRM OF UPRIGHT GATE COMPANY, OF QUINCY, ILLINOIS.

GATE.

Application filed December 15, 1925. Serial No. 75,631.

This invention relates to gates and has for its object the provision of a device forming an enclosure for an entrance which may be operated manually from opposite sides of the enclosure with a small amount of force.

A further object of the invention is the provision of a gate pivotally mounted at one side of an entrance and weighted so that little force is required to initiate the opening or closing movement of the same and in which the operating means for aiding in actuating the gate would also simultaneously release a locking bolt for the gate.

A still further object of the invention is the provision of a simple, efficient, reliable and easily constructed device operating as a closure for an entrance and which may be disassembled and compactly bundled for shipment.

This invention will be best understood from a consideration of the following detailed description, in view of the accompanying drawings forming a part of the specification; nevertheless it is to be understood that the invention is not confined to the disclosure, being susceptible of such changes and modifications which shall define no material departure from the salient features of the invention as expressed in the appended claim.

In the drawings:

Figure 1 is a view in perspective of a gate constructed in accordance with the principles of my invention and shown in operative position at an entrance.

Figure 2 is a fragmentary vertical section showing an element of the operating means.

Figure 3 is a sectional view of the latching means for the gate.

Referring more particularly to the drawings, 10 designates generally a gate formed in any well known manner, which has horizontal bars 11 and transverse vertical brace bars 12 and 13. The bars 13 are located at the free end of the gate and are curved as shown at 14 in order to permit ready oscillation of the gate without any interference from the post 15 located at one end of a fence 16.

At opposite sides of the other end of the gate 10 are mounted a pair of spaced posts 17 and 18. In spaced relation with each of the posts 17 or 18 is a second post 19

having a bifurcated upper end 20 in which is mounted a pulley 21. A pin 22 located above the pulley 21 cooperates with the pulley to prevent the displacement of a cable 23 which has at its free end a ring 24 and at its other end is connected to an oscillating lever 25 pivoted at 26 on the face of reinforcing plates 27 on the gate 10.

It will be noted that the cable 23 is employed at one side of the gate while a cable 23^a is employed at the opposite side of the gate for a purpose which will be presently explained. Each of these cables are passed around a pulley 28 supported on a post 17 or 18 and the posts 19 are braced by means of a horizontal bar 29 connected between the post and the inner posts 17 or 18. One end of the fence 30 is connected to the post 18.

A rather stout post 31 is mounted in a concrete base 32 at the rear of the posts 17 and 18 and is provided with a journal plate 33 having bearings 34 and 35 in which is mounted an axle 36. This axle is rigid with a hub 37 which is secured in any approved manner to the side plates 27 at the inner end of the gate. It will be noted that concrete sectors 38 are bolted to the inner free end 39 of the gate in such a manner that the weight of these sectors will be approximately sufficient to overbalance the weight of the gate 10 so that when the bolt 40 is released from a keeper in the post 15 by actuation of either of the cables 23 or 23^a the gate will tend to rise at its free end and be moved to substantially a vertical position so that vehicles may pass along the roadway.

The bolt 40 is pivotally mounted on a pin 41 and the U-shaped connecting link 42 has pivotal connections in any one of a plurality of perforations 43 in the bolt 40. The arms extend inwardly and are connected to links 45 which have pivotal connections with an end of the rock lever 25. The bolt is mounted in a casing 44 secured to a pair of bars 11 of the gate. A spring 46 is engaged by a lug 40^a of the bolt and maintains the free end of the bolt in projected relation so that it will be received by the keeper on the post 15 when the gate is in lowered position.

It will be seen by this construction that a very simple and inexpensive gate is pro-

duced which may be readily operated through either of the cables 23 or 23^a by exerting a slight pull on the cable for releasing the bolt 40 from the keeper in the post 15 whence the gate will rise. Due to the fact that the weights 38 are slightly greater than the weight of the gate 10 only a small amount of pull is required on either of the cables for causing the gate to return to its normal closed position. The position of the spaced posts 17 and 18 is such that when a sufficient pull is exerted on the cables which will tend to cause the gate to return to its downward position.

15 A form is supplied with each gate for making the sectors 38 of concrete so that the sectors may be manufactured at the point where the gate is erected and thus

eliminate the expense of shipping the concrete weights.

What I claim is:

A gate construction comprising a post, a plate rigid with the post and provided with bearings, an axle rotatably mounted in the bearings and provided with a hub, a gate having plates secured at one end and connected to the hub, weights connected to the plate at one side of the axle, a lever pivotally mounted on each plate, a cable connected with an end of each lever, a link connected with the other end of each lever, a spring pressed bolt pivotally mounted at one end of the gate, said link being connected with the spring pressed bolt.

JOHN E. W. FOGAL.
